REDUCING MILL

William M. Sheldon, Roselle Park, N. J., assignor
to Louis Ruprecht, Montclair, N. J.

Application June 2, 1938, Serial No. 211,333

5 Claims. (Cl. 83—11)

This invention relates to impact-type mills for pulverizing or comminuting moist clay, or ceramic body, or other moist materials containing sufficient moisture to be tacky and too little to be pasty. Clays containing 14 to 22% of moisture have such properties; they can be crumbled in the hand and yet are tacky enough to stick to a surface if projected against it at any considerable speed. For convenience, the term "moist clay" 10 will be used hereafter to designate such moist materials in general.

More particularly, the invention relates to reducing mills for operating on such material in which the material is fed by suitable means, most desirably by means of a conveyor belt, in a flat layer to the under side of a rotor having a series of circumferentially spaced hammers and mounted horizontally and driven at comparatively high speed so that the hammers strike the 15 end of the layer in the direction in which the layer is moving and throw a stream of the comminuted clay in a substantially horizontal direction. The product of reducing mills of this kind is for the most part very uniform and finely 20 comminuted. Some considerable difficulty has been experienced in the operation of such mills, however, from the fact that the product, otherwise highly satisfactory, has been found at times to contain flakes and lumps of the moist clay or 25 other tacky material of a size entirely disproportionate to the fine particles constituting the bulk of the product. The presence of these flakes and lumps in the product, I believe to be due to the fact that some of the clay as it is fed beneath the 30 rotor is beaten down on to the conveyor belt and caused to adhere thereto in the form of a compacted sheet, and that parts of this sheet then flake off as the belt bends downward about its supporting roll and are discharged with the finely 35 comminuted product; and, further, to the fact that some oversize lumps are struck by the hammers in such a way as to be thrown outwardly with the comminuted product only partially broken up or without having been broken up at all.

The object of the present invention is to prevent the discharge of such flakes or lumps with the finely comminuted product.

To this end, I provide the reducing mill with means whereby a self-adjusting retarding surface of the clay or other material being reduced which just clears or is scraped by the ends of the rotor hammers is maintained just beyond the line of closest approach of the hammer ends and the feed conveyor or other material-supporting 50 means cooperating with the rotor. This self-

adjusting retarding surface is obtained by mounting a wide cross-bar beneath the rotor just beyond the line of closest approach of the hammer ends and the cooperating material-supporting means, extending parallel with the rotor axis 5 and spaced a short distance away from the path of the hammer ends, and so formed that a layer of the clay or other material builds up thereon to an amount permitted by the rotating hammers and is thereafter maintained with an approximately zero clearance between its surface and the hammer ends. This retarding device formed by the cross-bar and its accumulated layer of clay or the like is the characterizing feature of reducing mills of the invention.

In the operation of the mill provided with such a retarding device, oversize agglomerations of the moist clay or the like are reduced by the rapidly moving hammers by coaction with the close-clearance retarding surface of compacted clay or 10 the like of the retarding device, with the result that the discharged product is without the objectionable flakes or lumps, being composed wholly of particles of the desired small size.

The retarding device cross-bar is so formed 15 and so positioned that a layer of the discharged material will be built up and maintained thereon extending transversely of the path of movement of the reduced material discharged by the rotor and extending circumferentially of and parallel 20 to the path of movement of the hammer ends from a line close to the material feed belt or other material-supporting surface cooperating with the rotor and just beyond the line of closest approach of the rotor hammers and the material-supporting surface. The form of bar I have so far found best has a flat portion facing the rotor and a flange along its far, or outer, upper edge.

The drawings show illustrative embodiments of the invention in a hammer mill of preferred construction for reducing moist clay and the like.

Fig. 1 is a plan view of the mill with a retarding device of the form now considered best;

Fig. 2 is a longitudinal sectional view taken on line 2—2 of Fig. 1;

Fig. 3 is a longitudinal sectional view on an enlarged scale of the rotor and retarding device and adjacent parts of the feed conveyor; and

Figs. 4 and 5 are views similar to Fig. 3 but showing modified forms of the retarding device.

Referring to the drawings, and first to Figs. 1, 2 and 3, the moist clay mill shown comprises a frame 10 having mounted therein a rotor 11 comprising a series of circumferentially spaced radially extending hammers, or beaters, 12 pivotally 55

mounted on a central hub on a shaft 11' by which the rotor is driven in the direction indicated by the arrow. Beneath the roller is a drum or roll 13 supporting one end of a horizontally extending rubber-surfaced conveyor belt 14, the other end of which belt is carried by a roll 15, the rolls and belt being driven by roll shaft 13'. Above the receiving end of the conveyor belt is a feed hopper 17 for receiving the moist clay to be comminuted and for depositing it on the feed belt. A rubber surfaced spreading roller 18 rotatably mounted between arms 19 extending forward from a shaft 20 pivotally mounted on the frame 10 above the conveyor belt serves to spread the clay on the belt in a layer of substantially uniform thickness.

Rubber-faced side guides 22 serve to keep the clay from spilling off the belt and to present the clay to the rotor in a layer of such limited width less than the axial length of the rotor that the edges of the layer of clay fed to the rotor shall not extend beyond either end of the rotor, and their end portions toward the rotor are adjustable laterally with respect to the belt by means of screws 23. The end portions of the guides adjacent the rotor are shaped to flare upwardly and outwardly as shown at 22' to catch the clay which may be carried around by the rotor and thrown down toward the edges of the feed belt.

The rotor is enclosed in a housing 25 which extends about the top, sides and ends of the rotor and has a lining 26 of soft rubber, and the peripheral wall of the casing is curved inward at the end adjacent the feed belt, as indicated at 27, in order to deflect forward the air current within the casing and thus avoid any backwardly directed current of air from striking the layer of material being fed forward on the feed belt.

The rotor is driven at relatively high speed so that, as the clay is fed thereto by the hammers and broken up, the comminuted clay is thrown outwardly in a substantially horizontal but somewhat upwardly inclined direction, and at considerable speed. The discharged comminuted material is collected on a rubber surfaced feed belt 28 which provides a collecting surface moving away from the rotor in the same general direction as the discharged particles and inclined upwardly at an angle to the horizontal somewhat less than that of the direction in which the particles are discharged by the rotor. The comminuted material will thus strike the collecting surface only after it has commenced to fall by gravity, and, because of the movement of the collecting surface, the relative movement between the collecting surface and the comminuted material at the moment of impact is reduced.

For a rotor having a diameter of 12", a suitable speed of rotation is about 3600 R. P. M., with the feed conveyor spaced about $\frac{3}{2}$ to $\frac{1}{8}$ inch from the peripheral path of the hammer ends and driven at about 25 to 30 feet per minute. The collecting belt is most desirably driven at about 125 to 150 ft. per minute.

A wide cross-bar 30 is mounted between the side members of the frame 10 to extend parallel with the rotor axis just beyond the line of closest approach of the rotor hammer ends and the feed belt, the feed belt at this line being supported by the roll 13. The bar 30 has at its far, or outer, upper, edge a flange 31 extending toward the rotor, and the surface of the bar facing toward the rotor is spaced somewhat away from the path of the hammer ends, so that in the operation of the mill comminuted clay will build up on the bar to the thickness permitted by the

rotating hammers, thus providing a layer 32 of the discharged material extending transversely of the path of movement of the material as discharged by the rotor, and extending circumferentially parallel to the path of movement of the hammer ends from close to the material feed belt just beyond the line of closest approach of the rotor hammers and the feed belt. The flange 31 serves to hold this built-up layer in place on the bar 30. The mill is thus provided with what I have termed a retarding device having a self-adjusting surface of the comminuted material lying across the path of discharge of the comminuted material and extending at approximately zero distance from the path of movement of the ends of the rotor hammers for a short distance circumferentially of the path of movement of the hammer ends from a line close to the feed belt, and this retarding device serves very effectively to prevent the discharge of flakes or oversized lumps with the finer comminuted product, as hereinbefore explained.

I have found it most desirable to have the clay-collecting surface of the bar 30 about 2" wide and spaced about $\frac{1}{4}$ to $\frac{1}{3}$ inch away from the path of movement of the hammer ends.

Instead of a bar 30 having a flange at its far edge for retaining the built-up layer of clay, a flangeless bar 30a may be used set at an angle as shown in Fig. 4, or a bar 30b extending parallel to the path of the hammer ends and without any retaining flange but having its surface suitably roughened, as by means of perforations therein, as shown in Fig. 5, may be used. These bars of Figs. 4 and 5 will serve to hold the built-up clay layer so that the desired self-adjusting retarding surface is maintained at approximately zero distance from the path of the movement of the hammer ends. A flanged cross-bar such as shown in Figs. 2 and 3 is, however, preferred.

What is claimed is:

1. In a mill for reducing moist clay and the like, the combination with a high speed rotor having a series of circumferentially spaced hammers, and means for feeding a layer of the moist material on a horizontally moving supporting surface to the under side of the rotor, and means for driving the rotor so that its hammers strike the layer of material in the same direction as such layer is moving but at a much greater speed, of a retarding device beneath the rotor and just beyond the line of closest approach of the ends of the rotor hammers and said material-supporting surface, said retarding device having a surface extending transversely of the path of movement of the reduced material discharged by the rotor in position to be struck by some of the discharged reduced material and formed to hold the layer of the material which builds up thereon, whereby during the operation of the mill a layer of the reduced material is maintained thereon having a self-adjusting surface extending parallel to the path of movement of the hammer ends at approximately zero distance therefrom and the inner edge of which is close to said supporting surface.

2. In a mill for reducing moist clay and the like, the combination with a high speed rotor having a series of circumferentially spaced hammers, and means for feeding a layer of the moist material on a horizontally moving supporting surface to the under side of the rotor, and means for driving the rotor so that its hammers strike the layer of material in the same direction as

- such layer is moving but at a much greater speed, of a retarding device beneath the rotor and just beyond the line of closest approach of the ends of the rotor hammers and said material-supporting surface, said retarding device having a surface extending transversely of the path of movement of the reduced material discharged by the rotor in position to be struck by some of the discharged reduced material and having a flange 5 at its far edge to hold the layer of the material which builds up thereon, whereby during the operation of the mill a layer of the reduced material is maintained thereon having a self-adjusting surface extending parallel to the path 10 of movement of the hammer ends at approximately zero distance therefrom and the inner edge of which is close to said supporting surface.
3. In a mill for reducing moist clay and the like, the combination with a high speed rotor 20 having a series of circumferentially spaced hammers, and means for feeding a layer of the moist material on a horizontally moving supporting surface to the under side of the rotor, and means for driving the rotor so that its hammers strike the layer of material in the same direction as such layer is moving but at a much greater speed, of retarding means comprising (a) a wide cross-bar extending parallel with the rotor axis beneath the rotor and just beyond the line of closest approach of the ends of the rotor hammers and the material-supporting surface and having a surface facing the rotor and spaced away from the path of the hammer ends with a flange at its far edge extending toward the rotor, and (b) 25 a layer of the reduced material on said bar providing a self-adjusting surface extending parallel to the path of movement of the hammer ends at approximately zero distance therefrom and the inner edge of which is close to said supporting surface.
4. In a mill for reducing moist clay and the like, the combination with a high speed rotor having a series of circumferentially spaced hammers, and means for feeding a layer of the moist material on a horizontally moving supporting surface to the under side of the rotor, and means for driving the rotor so that its hammers strike the layer of material in the same direction as such layer is moving but at a much greater speed, of retarding means beneath the rotor and just beyond the line of closest approach of the ends of the rotor hammers and said material-supporting surface, said retarding means comprising a member whereon a layer of the reduced material is maintained providing a self-adjusting surface 30 extending parallel to the path of movement of the hammer ends at approximately zero distance therefrom and the inner edge of which is close to said supporting surface.
5. In a mill for reducing moist clay and the like, the combination with a high speed rotor having a series of circumferentially spaced hammers, and a substantially horizontal belt conveyor for feeding a layer of the moist material to the under side of the rotor, and means for driving the rotor so that its hammers strike the layer of material in the same direction as such layer is moving but at a much greater speed, the conveyor belt being supported beneath the rotor by a roll about which the belt turns downward, of a retarding device mounted beneath the rotor and just beyond the line of closest approach of the ends of the rotor hammers and the feed belt comprising a member whereon a layer of the reduced material is maintained providing a self-adjusting surface extending parallel to the path of movement of the hammer ends at approximately zero distance therefrom and the inner edge of which is close to the conveyor belt.

WILLIAM M. SHELDON.
